Primary Examiner — Catherine Tuttle*(74) Attorney, Agent, or Firm* — Perkins Coie LLP(57) **CLAIM**

The ornamental design for the door-mounted basketball hoop, as shown and described.

DESCRIPTION

FIG. 1 is a front, top and left side perspective view showing my new design.

FIG. 2 is a front view.

FIG. 3 is a back view.

FIG. 4 is a right side view.

FIG. 5 is a left side view.

FIG. 6 is a top view; and,

FIG. 7 is a bottom view.

The broken lines are included for the purpose of illustrating portions of the door mounted basketball hoop that form no part of the claimed design.
